BUTTON

Morton Levine, Leominster, Mass., assignor to Commonwealth Plastics Corp., Leominster, Mass., a corporation of Massachusetts

Application May 27, 1954, Serial No. 30,695

Term of patent 3½ years

(Cl. D17—2)

Fig. 1

Fig. 2

Fig. 3

To all whom it may concern:

Be it known that I, Morton Levine, a citizen of the United States residing at Leominster, in the county of Worcester and State of Massachusetts, have invented a new, original, and ornamental Design for a Button, of which the following is a specification, reference being had to the accompanying drawings forming part thereof.

Fig. 1 is a top plan view of a button showing my new design.

Fig. 2 is a side view of the button.

Fig. 3 is a rear view of the button.

I claim:

The ornamental design for a button, as shown.
